ELASTIC FLUID GENERATOR ARRANGE-
MENTGünther Diedrich, Stettin, Germany, assignor to
General Electric Company, a corporation of
New YorkApplication June 29, 1937, Serial No. 151,017
In Germany July 7, 1936

1 Claim. (Cl. 122—24)

The present invention relates to elastic fluid generator arrangement of the type which includes a boiler and auxiliaries for operating the boiler and driven by a gas turbine receiving combustion gases discharged from the boiler. More specifically, the invention relates to arrangements including in addition to the gas turbine for driving the auxiliaries another prime mover such as an internal combustion engine.

10 The object of my invention is to provide an improved elastic fluid generator arrangement whereby better efficiency is attained and quick starting of the boiler assured. This is accomplished by my invention by the provision of an arrangement in which the exhaust gases discharged from both the boiler and the internal combustion engine are utilized for operating a single gas turbine.

For a better understanding of what I believe 20 to be novel and my invention, attention is directed to the following description and the claims appended thereto in connection with the accompanying drawing.

In the drawing Fig. 1 represents a diagrammatic view partly in section of an elastic fluid generator arrangement embodying my invention; Fig. 2 is a sectional view along the line 2—2 of Fig. 1; and Fig. 3 illustrates a modification of a part of Fig. 1.

30 The arrangement as shown in Figs. 1 and 2 comprises a boiler 10 including a heating element 11 for heating liquid to be evaporated and a burner 12 for supplying a mixture of fuel and air to the boiler. The heating element 11 has an inlet connected by a conduit 13 to a pump 14 for forcing liquid through the element 11. The burner 12 has an inlet conduit 15 for receiving fuel from a fuel pump 16 and another inlet conduit 17 for receiving air from a blower or compressor 18. The blower 18 together with the boiler feed pump 14 and the fuel pump 16 are arranged on a common shaft 19 which is driven by a gas turbine 20. The latter has a bucket wheel 21 secured to a shaft 21a and a nozzle box 22 forming a row of nozzles 23 for properly directing gases from the nozzle box to the buckets of the wheel 21. The nozzle box 22 is connected by a conduit 24 to the boiler to receive combustion gases discharged therefrom. The turbine shaft 21a is suitably coupled to the shaft 19 of the auxiliaries.

50 As a means for starting the auxiliaries and as an additional drive means for the auxiliaries an internal combustion engine 25 is provided and suitably connected to the drive shaft 19 for the auxiliaries, in the present instance through the

intermediary of the gas turbine shaft 21a. The engine 25 has an exhaust conduit 26 which in accordance with my invention is connected to the nozzle box 22 to discharge exhaust gases into said box and thereby to permit utilization of the 5 available energy of these exhaust gases.

In the arrangement of Figs. 1 and 2 the exhaust gases from the engine and from the boiler are mixed in the nozzle box whereby the temperature of the exhaust gas from the engine is 10 lowered and that of the boiler raised. Both of these effects are desirable in that first they prevent the setting up of high stresses in the gas turbine due to the high temperature of the exhaust gases from the engine and second they 15 permit efficient operation of the boiler in that the available energy in the combustion gases of the latter may be utilized to a greater extent in the boiler.

The available heat energy in the gases discharged from the gas turbine through a conduit 20 21 is utilized to preheat the air conducted to the inlet of the blower 18. To this end a heat exchanger 28 is provided through which the gases discharged from the gas turbine are conducted 25 to effect heat exchange with air flowing from the atmosphere through the heat exchanger to the inlet of the blower 18. The preheating of the air to be forced by the blower 18 to the burner 12 facilitates starting operation in that it reduces the starting period.

During starting the auxiliaries 14, 16, 18 are driven by the gas turbine 20 which during this condition is operated by gases discharged from the engine 25. As soon as the boiler 10 is started 35 and combustion gases are formed these gases are conducted to the nozzle box 22 as an additional power supply for the gas turbine. During normal operation and low load condition the engine 25 may be disconnected. The exhaust conduit 40 26 of the engine 25 is preferably arranged so that the gases discharged from the nozzle box are directed directly towards the nozzles 23 and in addition the outlet end of the exhaust conduit 26 is preferably arranged to form a nozzle and thereby to cause a suction effect on the combustion gases in the boiler. The advantage of creating a suction effect by the exhaust gases of the engine is especially noticeable during the starting period 45 of the boiler during which fresh air will be rapidly drawn through the boiler as a result of the injector action even before the blower is coupled to the exhaust gas turbine.

The modification in Fig. 3 shows a nozzle box 38 with nozzles 31 and other nozzles 32. In ad- 50

- dition the box includes a partition 33 arranged to form two spaces in the nozzle box so that the combustion gases discharged from the boiler through the conduit 24 are conducted to one of the spaces including the nozzles 31, whereas exhaust gases from the engine 25 are conducted to the other space including the nozzles 32. In this arrangement no mixing of the two kinds of gases takes place.
- 10 Having described the method of operation of my invention, together with the apparatus which I now consider to represent the best embodiment thereof, I desire to have it understood that the apparatus shown is only illustrative and that the invention may be carried out by other means.
- 15

What I claim as new and desire to secure by Letters Patent of the United States is:

Elastic fluid generator arrangement including the combination of a boiler, auxiliaries for operating the boiler, a gas turbine with a nozzle box 5 and an internal combustion engine for driving the auxiliaries, conduit means for conducting combustion gases from the boiler to the nozzle box, and conduit means forming an ejector with- in the nozzle box to discharge gases from the 10 engine to the nozzle box and to effect ejection of gases from the boiler.

GÜNTHER DIEDRICH.
